UNITED STATES PATENT OFFICE.

AUGUSTUS J. DUPUIS, OF DETROIT, MICHIGAN.

STEAM PILE-DRIVER.

SPECIFICATION forming part of Letters Patent No. 341,837, dated May 11, 1886.

Application filed October 26, 1885. Serial No. 181,037. (No model.)

To all whom it may concern:

Be it known that I, AUGUSTUS J. DUPUIS, of Detroit, county of Wayne, State of Michigan, have invented a new and useful Improvement in Steam Pile-Drivers; and I declare the following to be a full, clear, and exact description of the same, such as will enable others skilled in the art to which it pertains to make and use it, reference being had to the accompanying drawings, which form a part of this specification.

My invention consists of the combinations of devices and appliances hereinafter specified, and more particularly pointed out in the claims.

In the drawings, Figure 1 is a sectional view, and Fig. 2 a side elevation at right angles to Fig. 1, of a device embodying my invention. Fig. 3 is a horizontal section through the cylinder, and Fig. 4 a section just above the latter.

My invention consists in the several novel features of construction and combination of parts, hereinafter fully described, and definitely pointed out in the claims annexed to this specification.

In carrying out my invention, A represents the portion which rests upon and surrounds the head of the pile, which I term the "ferrule."

B is the steam-cylinder.

B' are uprights connecting the ferrule with the cylinder.

C is the plunger, formed at C' into a piston-head adapted to travel within the cylinder.

D is a steam-chest; E, a rotary valve within the steam-chest.

e e' are steam-ports leading to opposite ends of the cylinder.

e² is the exhaust-port, open to the external air at e³, or other convenient point, as shown in Fig. 3. A valve, E, (shown in Fig. 1,) is provided with a bridge of any usual form adapted to span over the exhaust-port and

either of said steam-ports alternately, so that when in the position shown in the drawings steam may enter beneath the piston of the plunger and be exhausted from the space above the piston, and when the valve is rotated downward it will cut off steam from beneath the piston and connect this port with the exhaust, at the same time admitting live

steam above the piston. The valve E is provided with two crank-arms, E' E², as shown in Figs. 1 and 2, whereby the valve is rotated. 55

F is a valve-shifting bar, provided at its upper and lower ends with cam-shaped projections f f'. This bar is connected so as to move up and down with the piston, and it is apparent upon inspection of Fig. 1 that when 60 the piston is raised from the position shown the valve E will remain in the position indicated until the cam f impinges against the crank arm E. It will then operate to rotate the valve over to the right and change the relation of the ports, as above explained, and on the downward motion of the plunger the valve will remain in this position until the cam f' strikes the other crank-arm, E², which will rotate the valve back to the position shown in 70 the drawings.

The uprights B' are provided with upwardly-projecting flanges B², which engage with suitable ways upon the usual frame-work, (not shown, but employed with all pile-driving 75 devices for locating the uprights over the pile and driving it in order that it may fall down as the pile is driven.)

F' is a collar formed in two pieces, so as to be fitted around and within the corresponding 80 annular groove in the plunger. They are held together in place by an outer tightening-band, F². This may be secured in any suitable way, although I have found it convenient to slightly taper the collar F', and also the tightening-band, and then to simply drive the latter and cause it to wedge upon the collar. An arm, F³, projects from the tightening-band, to which arm the valve-shifting bar F is connected. This tightening-band is also provided with 90 projections f², which engage suitable guides, f³, upon the uprights B', in order to give direction to the extremity of the plunger, and to prevent any rotation of the plunger from disturbing the proper position of the valve-shifting bar F. 95

The operation of the device is as follows: The apparatus is connected by the lifting-ring H to suitable hoisting mechanism, and is hoisted to its proper position over the pile that is 100 to be driven. It is then lowered down between its guides until the ferrule rests upon the top of the pile, the pile being usually dressed off so as to enter the cavity in the fer-

rule. Steam is now admitted through a suitable steam-hose into the steam-chest. The valve being in the position shown in Fig. 1, steam enters thence to the space beneath the piston 5 and lifts the plunger quickly upward to its position. Just as it reaches this point, however, the projection *f* on the bar *F* shifts the valve so as to cut off steam from beneath the piston and connect this space with the exhaust, 10 the same movement cutting off the exhaust from the space above the cylinder and permitting live steam to enter. As soon as the steam is cut off and the exhaust connected with the space below the piston, the plunger drops of 15 its own gravity; but the live steam entering above the piston gives it the impetus due to the full steam-pressure, and so delivers a blow very greatly in excess of the blow that would have been delivered by the plunger alone. 20 As soon as the plunger reaches the bottom of its travel and delivers its stroke, the projection *f'* on the bar *F* will have shifted the valve, causing the cylinder to again take steam beneath the piston and exhaust from above the 25 piston. The device therefore works rapidly in delivering its blow until steam is turned off from the steam-hose, each time adding the power of the steam in delivering the blow to the gravity of the plunger itself. 30 I have described a rotary valve in this connection. It is apparent, however, that any suitable valve mechanism may be employed instead of a rotary valve, and I have also described the valve-shifter bar connected directly 35 with the plunger, as a means for shifting the valve and causing it to change the relation of the ports. It is apparent, however, that any other suitable valve-shifting mechanism might be employed, although I prefer such mechanism as shall have motion imparted to it by the plunger, either directly or indirectly, and would therefore have it understood that my invention contemplates such modifications as I have suggested. 40 The piston and plunger are preferably made in a single piece integral with each other. 45

This prevents all liability to breakage or derangement, such as would exist if the piston were made separable from the plunger.

What I claim is—

50 1. A steam pile-driver provided with steam-ports leading to both ends of the cylinder, and an exhaust communicating with both steam-ports, a valve-chamber, a rotary valve within the same, a double crank on the stem of the valve, and a side bar operated by the plunger, and having cams which actuate said cranks, substantially as described.

2. A steam pile-driver having a rotary valve, 60 a double crank on the stem of said valve, a slide-bar having cams which actuate said cranks, and a collar connecting said slide-bar to the plunger, the parts being combined substantially as described.

3. A steam pile-driver having a rotary valve, 65 a double crank mounted on the stem of the valve, a slide-bar actuating said crank, a collar connecting said bar to the plunger, and projections on the collar engaging with guides on the uprights, substantially as described. 70

4. In a steam pile-driver, the combination, with a rotary valve and a slide-bar operating said valve, of a collar connecting said bar with the plunger, and a second two-part collar fitted within a recess in the plunger and embraced 75 by the outer collar, substantially as described.

5. In a steam pile-driver, the combination, with the steam-cylinder and a ferrule for supporting the head of the pile, of uprights connecting the two guides upon said uprights, a 80 collar having projections engaging with said guides, a plunger carrying the collar, a slide-bar connected with the latter, and a rotary valve operated by cams on said rod, substantially as described.

85 In testimony whereof I sign this specification in the presence of two witnesses.

AUGUSTUS J. DUPUIS.
